BODY SUPPORTING GARMENT

Albert H. Searles, Kalamazoo, Mich., assignor to
Grace Corset Company, Kalamazoo, Mich.

Application July 29, 1949, Serial No. 107,534

3 Claims. (Cl. 2—27)

1

This invention relates to improvements in body supporting garments such as corsets, abdominal supports, brassières, garter belts, girdles, foundation garments and the like.

The main objects of this invention are:

First, to provide a body garment of the corset, foundation garment, abdominal support, brassière, girdle, garter belt, and the like, in which the front portion is provided with effective supporting boning, at the same time providing a maximum of comfort and freedom of movement for the wearer.

Second, to provide a body garment of this type which may be produced at relatively low cost.

Third, to provide a body garment of the class indicated having cross boning providing an effective support with all excessive strain either on parts of the garment or on the wearer.

Objects relating to details and economies of the invention will appear from the description to follow. The invention is pointed out in the claims.

A preferred embodiment of the invention is illustrated in the accompanying drawings, in which:

Fig. 1 is a front elevational view of a body garment embodying my invention.

Fig. 2 is an enlarged fragmentary view in horizontal section on a line corresponding to line 2—2 of Fig. 1.

Fig. 3 is a fragmentary elevational view with parts broken away and in section to show structural details.

Fig. 4 is an enlarged vertical section on a line corresponding to line 4—4 of Fig. 1.

Fig. 5 is a fragmentary front elevational view of a somewhat modified form or embodiment of my invention, the part being broken away to show structural details.

Fig. 6 is a fragmentary elevational view of still another modification or embodiment of my invention.

The embodiment of my invention illustrated in Fig. 1 comprises a back portion 1, side portions 2—2, these side portions being of elastic material, and a front portion complementing the side and back portions. The back and side portions illustrated are or may be conventional.

The front portion comprises an inner front panel 4 fixedly secured along one vertical edge 5 to the front edge of one side portion and detachably secured to the front edge of the other side portion as is indicated by detachable fastenings 6 shown by dotted lines in Fig. 1. These fastenings may be of a conventional or of known

2

types. The front panel 4 is provided with a central A-shaped notch extending from its lower end and filled with the elastic gusset 7. The lower edge of the panel 4 and the edges of the notch thereof are provided with bindings 8 and 9.

The boning panels 10 are disposed outwardly of the inner panel 4 and in overlapping relation thereto as shown in Figs. 1, 2 and 3, and are secured at their outer vertical edges to the inner panel 4 and are disposed with substantial inner portions 11 thereof in overlapping relation. The edges of these boning panels are secured together by the continuous binding 12 while their upper edges are secured at 13 to the upper edge of the inner panel 4. The lower edges of the boning panels are desirably substantially spaced from the lower edge of the inner panel 4. The boning panels are free for independent movement relative to each other except as connected by their bottom and top edge connections 12 and 13.

The boning panels are provided with a plurality of parallel boning pockets 14 arranged in a vertically inclined relation with the boning pockets of one boning panel in diagonal crossing relation to those of the other panel as is clearly shown in the drawing. The panel pockets are provided with suitable boning elements 15. It will be noted by reference to Figs. 1 and 3 that the boning elements 15 generally of one panel 10 are disposed on approximately the same level with the level of the elements 15 generally of the other panel 10. It will be understood that I use the term boning in its generic sense and as generally used in the industry, that is, the stiffening elements may be of steel, bone, wire or other suitable resilient stiffening material.

In the embodiment shown in Fig. 1, the boning pockets of each boning panel are in parallel spaced relation. In the embodiment shown in Fig. 5 the boning pockets 16 are double pocket type, that is, they are formed of material of a width to provide two pockets separated by rows of stitches 17 centrally thereof. In the embodiment shown in Fig. 6 the pockets 18 are of the triple type while the pockets 19 are of the double type. In all of these embodiments the overlapping portions of the boning panels are free from each other permitting independent movement which greatly adds to the comfort of the wearer while providing an effective support.

The garment illustrated in Fig. 1 is provided with hose supporters 20. The applicant is aware that crossed boning as such is old in body garments but such crossed boning, so far as applicant's knowledge goes is built into a single panel.

With applicant's invention the double boning panels may be very easily and economically produced and easily and economically assembled in the garment. In addition to that the structure while providing an effective support affords a high degree of comfort to the wearer also the garment is very durable inasmuch as the strain on the parts is minimized.

I have illustrated and described my improvements in a highly practical commercial embodiments thereof. I have not attempted to illustrate the embodiment of my invention in various types and styles of body garments such as brassières, garter belts, girdles, front and back lace corsets and the like, as it is believed that this disclosure will enable those skilled in the art to embody or adapt my invention as may be desired.

Having thus described my invention, what I claim as new and desire to secure by Letters Patent is:

1. A body garment of the class described comprising rear, and side portions and a complementary front portion, said side portions having vertical front edges, the front portion comprising an inner panel having upper and bottom edges and vertical side edges, one of said vertical side edges of the inner panel being detachably joined to a vertical front edge of one side portion, a pair of boning panels disposed outwardly of and in overlapping relation to said inner front panel and having outer vertical edges connected to the vertical side edges of the inner panel, said boning panels having inner edge portions disposed in overlapping relation to each other centrally of the inner panel and having upwardly inclined inner edges disposed in crossing relation to each other, the upper edges of the boning panels being secured to the upper edge of the inner front panel and the lower edges of the boning panels being secured together and being substantially spaced from the bottom edge of the inner front panel, the overlapping portions of the boning panels being independently movable relative to each other except as restrained by the said top and bottom connections therefor, said boning panels having a plurality of diagonally disposed parallel boning pockets, there being a boning pocket at the inner edge of each boning panel, and resilient boning elements disposed in said pockets, the boning elements of one boning panel being in diagonally crossed lapping relation to the boning elements of the other boning panel, the upper end portions of the boning elements of one boning panel being disposed generally on approximately the same level with that of the upper end portions of the boning elements of the other boning panel, and the lower end portions of the boning elements of one boning panel being disposed generally on approximately the same level with that of the lower end portions of the boning elements of the other boning panel.

2. A body garment of the class described comprising rear, and side portions and a complementary front portion, said side portions having vertical front edges, the front portion comprising an inner panel having upper and bottom edges and vertical side edges, a pair of boning panels

disposed outwardly of and in overlapping relation to said inner front panel and having outer vertical edges connected to the vertical side edges of the inner panel, said boning panels having inner edge portions disposed in overlapping relation to each other, the upper edges of the boning panels being secured to the upper edge of the inner front panel and the lower edges of the boning panels being secured together and being substantially spaced from the bottom edge of the inner front panel, the overlapping portions of the boning panels being independently movable relative to each other except as restrained by the said top and bottom connections therefor, said boning panels having a plurality of diagonally disposed parallel boning pockets, and resilient boning elements disposed in said pockets, the boning elements of one boning panel being in diagonally crossed lapping relation to the boning elements of the other boning panel, the upper end portions of the boning elements of one boning panel being disposed generally on approximately the same level with that of the upper end portions of the boning elements of the other boning panel, and the lower end portions of the boning elements of one boning panel being disposed generally on approximately the same level with that of the lower end portions of the boning elements of the other boning panel.

3. In a body garment of the class described, rear, side and front portions, the front portion comprising a pair of boning panels connected at their outer vertical edges to the side portions, said boning panels having crossing inclined inner edges disposed between said outer vertical edges and extending between the upper and lower edges of the boning panels, each boning panel having a plurality of parallel boning pockets and boning elements in said pockets, the boning pockets and boning elements of one panel crossing the boning pockets and boning elements of the other panel, one of said boning pockets and a boning element therein of each boning panel being disposed parallel to and adjacent the inner edge of the panel, the inner edge portions of the overlapping boning panels adjacent said inner edges and intermediate the top and bottom edge of the panels being free to move relative to each other, the boning elements generally of one boning panel being disposed approximately on the same level with the level of the boning elements generally of the other boning panel.

ALBERT H. SEARLES.
